United States Patent Office

Des. 195,404
Patented June 11, 1963

195,404

MAGNETIC TAPE UNIT OR SIMILAR ARTICLE

Gene S. Tepper, San Francisco, and John M. Wernli,
Menlo Park, Calif., assignors to Datamec Corporation,
Mountain View, Calif., a corporation of California

Filed Dec. 17, 1962, Ser. No. 72,878

Term of patent 14 years

(Cl. D26—5)

FIG. 1

Des. 195,404

PAGE 2

FIG. 3

FIG. 1 is a partial front perspective view of a magnetic tape unit showing our new design;

FIG. 2 is another front perspective view thereof; and

FIG. 3 is a front perspective view with the panel door shown in open position.

The essential features of the design reside in the portions shown in solid lines.

We claim:

The ornamental design for a magnetic tape unit or similar article, substantially as shown and described.
